UNITED STATES PATENT OFFICE.

FREDERICK KLEIN, OF COLLEGE POINT, NEW YORK, ASSIGNOR TO NATIONAL INDICATOR COMPANY, OF LONG ISLAND CITY, NEW YORK, A CORPORATION OF NEW YORK.

TENSION MECHANISM FOR BRAIDING MACHINES.

Application filed August 30, 1923. Serial No. 660,144.

To all whom it may concern:

Be it known that I, FREDERICK KLEIN, a citizen of the United States, and resident of College Point, in the borough of Queens, city, 5 county, and State of New York, have invented certain new and useful Improvements in Tension Mechanisms for Braiding Machines, of which the following is a specification.

10 This invention relates to a yarn or thread tension mechanism for that type of braiding machine in which two oppositely rotating tables or turrets are provided, each turret or table carrying a series of spools or bobbins, the threads from all of said spools converging at a braiding point above the machine and means being provided whereby the threads from one series of bobbins will be interlaced with the threads from the other 15 20 25 series of bobbins. The purpose of machines of this type is to produce a tubular braided fabric with or without a core.

The purpose of this invention is to provide a sensitive and positive yarn control 25 particularly adapted for use on high-speed braiding machines.

One of the main objects of the invention is to provide means whereby the tension member is in direct contact with the yarn, 30 without levers or other transmission elements interposed between the yarn and the tension member.

Another object of the invention is to so control the yarn supply as it is being used 35 during the operation of braiding that the release, or the locking, of the yarn supply will not materially affect the predetermined tension on the yarn. This is of special importance when operating at low tensions as 40 the action must be smooth and uniform, yet positive.

Another object of the invention is to provide a simple and efficient means by which any required tension may be obtained, and 45 to provide means cooperating with the tension member to cause the machine to stop when the desired tension is suddenly and materially changed; when the yarn breaks, or when the yarn supply becomes exhausted.

50 Another object of the invention is to provide a tension mechanism within a minimum of space and wherein the parts will be easily accessible.

In the accompanying drawings, Figure 1 55 is a vertical sectional view of a portion of

a braiding machine with the invention applied thereto;

Fig. 2 a plan view of a portion of the machine shown in Fig. 1;

Fig. 3 a perspective view of one of the 60 outer bobbin carriers with the tension mechanism applied thereto;

Fig. 4 a detail sectional view of the tension spring and its adjusting means;

Fig. 5 a vertical sectional view of a bobbin 65 carrier and the tension mechanism;

Fig. 6 a horizontal sectional view taken on the line 6—6 of Fig. 5;

Fig. 7 a detail plan view of the tension 70 spring and the escapement lock;

Fig. 8 a perspective view of the parts shown in Fig. 7;

Fig. 9 a perspective view of the clutch operating devices;

Fig. 10 a vertical sectional view similar 75 to Fig. 5, showing the clutch operating means released by the breaking of a thread;

Fig. 11 a detail plan view showing the operation of the escapement lock when the control lever is released by the breaking of 80 a thread;

Fig. 12 a horizontal sectional view taken on the line 12—12 of Fig. 10;

Fig. 13 a perspective view showing the clutch releasing means in the position illustrated in Figs. 10 and 12; 85

Fig. 14 a vertical sectional view similar to Fig. 5, showing the clutch releasing means operated by an excessive tension on the thread;

Fig. 15 a plan view of the tension spring, escapement lock and the control lever in the position shown in Fig. 14;

Fig. 16 a horizontal sectional view taken on the line 16—16 of Fig. 14; and 95

Fig. 17 a perspective view of the control lever and the clutch releasing means in the position shown in Figs. 14 and 16.

The invention is shown as applied to a braiding machine of the type illustrated in 100 Patent No. 1,493,782, issued May 13, 1923.

Referring to the various parts by numerals, 2 designates an upward extending tubular post which is rigidly mounted at its lower end in the base of the machine. A 105 horizontal drive shaft 3 is also mounted in the base of the machine, and this shaft carries a pulley 4 at its outer end adapted to be engaged by a suitable clutch 5, to connect the said pulley to the drive shaft. A 110

beveled driving pinion 6 is mounted on the inner end of the drive shaft, said pinion 6 engaging two beveled gears 7 and 8 and by means of which the bobbin-carrying turbines are rotated in opposite directions, as will be fully hereinafter described.

Rotatably mounted upon the post 2 is an inner driving sleeve 9 to the lower end of which the beveled gear 8 is rigidly secured. Mounted on the sleeve 9 is an outer drive sleeve 10 which carries near its lower end the beveled gear 7. It is manifest from this construction that the driving sleeves 9 and 10 will be rotated in opposite directions, the drive pinion 6 being arranged between said beveled gears. The driving pinion 6 and the beveled gears 7 and 8 are preferably located within the base of the machine for safety and for convenience of 20 oiling.

Rigidly secured to the outer driving sleeve, at a suitable point above the base, is an outwardly and downwardly flaring circular turret plate 11. To the outer margin of this turret plate is secured a series of upwardly extending arched bobbin supports 12, the lower ends of the two arms of these supports being substantially coincident with the lower margin of the circular turret plate 11. These supports 12 are spaced equal distances apart around the turret. To the lower ends of the outer members of these arched supporting plates are secured carriers 13 which support the outer bobbins or thread carriers 14. These outer bobbins are supported on horizontal spindles 15 mounted in suitable bearings in the carriers 13. The carriers 13 are connected together around the machine by brace bars 16.

40 The inner driving sleeve 9 carries on its upper end a spider frame 17 formed with radial arms 18 which extend outwardly and downwardly, as shown clearly in Figs. 1 and 2 of the drawings. The lower outer end of each of these spider arms is tubular and forms a bearing for a short radially arranged shaft 19, said shaft extending outwardly and downwardly. To the upper end of each of said shafts 19 is secured a beveled pinion 20. Rigidly secured to the upper end of the outer driving sleeve, just under the spider 17, is a crown gear 21 which meshes with all of the pinions 20. Rigidly secured to the outer lower end of each shaft 19 is a carrier-supporting disk 22, each of said supporting disks being formed around its margin with an outwardly turned annular flange 23. Each of said supporting disks is formed with thread-receiving-and-carrying notches 24.

55 The bobbins 25 of the inner series are each mounted in a carrier frame consisting of an upper carrier head 26; two outwardly and downwardly diverging side bars 27 connected to said head, and a large outer

shuttle plate 28 rigidly connected to the lower ends of the side bars 27. Each shuttle plate 28 is substantially elliptical in form with its longer axis horizontal and its end pointed. The side bars 27 are connected to the shuttle plate 28 near the ends of said plate. The carrier heads 26 are also substantially elliptical in form with their longer axis substantially horizontal, and the side bars 27 are connected to said heads 26 near their ends. Each carrier head 26 is arranged between two adjoining supporting disks 22 and is adapted to be engaged with and supported by said disks.

60 The construction and operation of the mechanism hereinbefore described are fully illustrated and described in the aforesaid patent and need not be more fully described herein.

65 Each carrier 13 consists of a hollow body part 29 provided at its inner end with a grooved bracket 30 to receive the outer member of one of the supports 12, a screw 31 securing the two parts together. The body part 29 is open at its outer end and said end is closed by a cover 32, screws 33 securing said cover in place. Extending substantially vertically across the outer open end of the body 29 is a control lever 34, said lever being held in place by the cover. In the upper and lower edges of the cover are formed slots to hold the lever in place and to form bearings in which said lever rocks. The lower slot is elongated to permit the lever to have a bodily outward movement 100 at its lower end, as will be hereinafter described.

70 The control lever is formed near its upper and lower ends with bearing portions 35 and 36, bearing portion 35 rotating in a recess 37 in the upper wall of the cover and portion 36 rotating in a slot 38 in the lower wall of the cover. Above the cover the control lever is bent laterally to form a tension arm 39, the end of said arm being formed with a substantially vertical loop or bail 39^a to receive the free end of the tension spring. The lower end of the control lever, below the cover, is bent laterally to form a stop 40, said stop and the tension arm serving as means to prevent undue endwise or axial movement of the lever in its bearings. Within the body of the carrier 13 the control lever is formed with an escapement operating arm 41, said arm being in the form of a crank and located near the upper wall of the cover. Below the escapement operating arm, and within the carrier 13, the control lever is formed with a clutch operating arm 42. This clutch operating arm is in the form of a crank which extends in a direction opposite to the escapement operating arm 41. The control lever is free to oscillate in both directions and when moving in one direction it oper-

75 80 85 90 95 100 105 110 115 120 125 130

ates the escapement controlling devices and when moving in the opposite direction it operates the clutch releasing mechanism, both of these movements being under the 5 control of the yarn and the tension spring which is connected to the tension arm, all of which will be more fully hereinafter described.

One end of each of the spindles 15 is provided with a rigidly connected escapement wheel 43. The end of the spindle adjacent the escapement wheel is adapted to enter a bearing slot 44 formed in the adjacent side wall of the body part 29 of the carrier, 10 said bearing slot opening on its lower side into a substantially horizontal slot 45 formed in the carrier body. Mounted in the slot 45 is a beveled head 46 which is adapted to close the lower side of the bearing slot 20 44 and lock the spindle end in its bearing. The head 46 is mounted on a spring-pressed pin 47 which is provided with a push button 48, and the outer side of said head is beveled as shown clearly in Figs. 3 and 16. 25 The spring-pressed pin 47 is mounted in the cover 32 and said pin and the head 46 are removable with said cover. On the opposite side of the carrier from the bearing slot 44 is formed a bearing 49 to receive 30 one end of one of the spindles 15. As shown in Fig. 2 the spindles 15 bridge the space between adjoining carriers 13. To place a spindle in position one end thereof is inserted in the bearing 49 of one carrier and 35 the opposite end thereof, the end carrying the escapement wheel 43, is passed into the slot 45 and pressed against the beveled outer surface of the head 46. The head 46 is forced inwardly until the spindle snaps up 40 into the slot 44. The head will then be forced outwardly by its spring and thereby lock the spindle in position. To remove a spindle it is only necessary to force the head 46 inwardly by pressure upon the push button 48 to thereby free the spindle and allow 45 it to drop down into the slot 45. The freed end of the spindle may be then drawn forwardly out of the slot 46, thereby freeing the opposite end of the spindle from its 50 bearing 49.

A double escapement dog 50 is loosely mounted on a bearing 51 secured to the side of the body 29 of the carrier and is adapted to engage the teeth of the escapement wheel, 55 as shown clearly in Fig. 8. One end of the escapement dog is extended upwardly to form a locking member 52, said member being provided on its outer face with fine horizontal teeth or serrations 53. As the 60 escapement dog is rocked on its bearing its ends will alternately engage the teeth of the escapement wheel in the usual way and similar to a clock escapement dog.

On the top of the carrier body is rigidly 65 secured and upwardly extending post 54.

Coiled about this post is a tension spring 55 similar to a clock spring and having its inner end rigidly secured to a rotatable sleeve 56 mounted on said post. The sleeve 56 is provided with a thumb nut 57 by 70 which it may be turned for the purpose of varying the tension of the spring. The upper surface of the nut 57 is radially serrated and rigidly connected to the post is a lock spring 58 adapted to fit in said serrations and to lock the thumb nut and the sleeve in their adjusted positions. The outer free end of the spring 55 is carried through the loop 39^a formed on the outer free end of the tension arm 39. To the end of the 80 spring, beyond the loop 39^a, is secured a hook 59 adapted to be engaged by the yarn, as will be hereinafter described.

Within the carrier 13 is arranged an escapement locking lever 60, said lever being 85 in substantially the same horizontal plane with the locking member 52 of the escapement dog and the escapement operating arm 41 of the control lever. The lever 60 is formed with bearing lugs 61 which fit in recesses formed in the inner margin of the cover portion 32, the cover serving as means for securing the lever in position. The inner end of the lever 60 is adapted to be engaged by the escapement operating arm 41. 90 The outer end of this lever extends beyond the carrier 13 and is provided with a serrated face 62 adapted to engage with the serrated locking face 52 of the escapement dog. A light spring 63, mounted within 100 the cover portion of the carrier and bearing at its free end on the outer end of the lever 60, tends to swing said lever into position to interlock its serrated face with the locking member 52. When the yarn is threaded 105 through the hook 59 and the proper tension is placed thereon the control lever will be rocked, as indicated in Fig. 7, and the escapement operating arm 41 will engage the inner end of the locking lever 60 and swing 110 it sufficiently to release the locking member 52, as indicated clearly in Figs. 7 and 8. When, however, the tension on the yarn is reduced below the predetermined point fixed by the tension spring, the control lever 115 will be rocked in the opposite direction by the tension spring, thereby withdrawing the escapement operating arm 41 from the lever 60 and allowing the spring 63 to force said lever into locking engagement with the locking member 52 of the escapement dog. This will lock the escapement wheel and prevent the unwinding of the yarn from the spindle 15. This operation of locking the escapement dog will take place whenever 120 there is undue slack in the yarn and whenever the yarn breaks.

A clutch releasing lever 64 is pivotally mounted on a horizontal pivot 65 in the lower end of the carrier body. The out- 125

wardly extending portion of said lever is enlarged vertically and to said enlarged part is rigidly connected a weight 66, said weight tending to depress the outer end of the lever and to raise the inner end thereof. To the inner end of the lever 64 is swiveled a pin 67, said pin being adapted to be projected downwardly into the path of a clutch lock 68, shown in Fig. 1 and indicated by 10 dotted lines in Fig. 10. The lever 64, at its outer end, beyond the weighted portion, is formed with an upwardly extending locking finger 69. Pivotally mounted within the carrier, on the bottom wall of the cover, 15 is a clutch lever lock 70. This lever is formed with a U-shape, substantially horizontal locking finger 71, one member of which is adapted to engage the upper edge of the locking finger 69 and thereby hold the 20 outer end of the clutch releasing lever 64 depressed, as indicated in Figs. 5 and 9. This results in holding the pin 67 elevated and out of the path of the clutch lock 68. The outer member of the U-shape locking 25 finger 71 lies in the path of the clutch operating arm 42 of the control lever, as shown clearly in Figs. 5, 9 and 13. The lower bearing portion 36 of the control lever passes through the clutch lever lock 70, as shown 30 clearly in Figs. 5, 9 and 13. When the yarn is slack, and when it breaks, the control lever will be rocked by the spring 55 and the arm 42 will be swung inwardly into engagement with the outer member of the U- 35 shape locking finger 71 and the clutch locking lever 70 will be swung inwardly on its pivot. The lower end of the control lever is pivoted in the lever lock 70 and will be swung inwardly as said lever moves on its 40 pivot, the slot 38 permitting the inward bodily movement of the lower end of the control lever. The inward swinging movement of the clutch lever lock will move the inner member of the finger 71 away from 45 and out of contact with the finger 69 of the clutch releasing lever 64. Because of the weight 66 the outer end of the lever 64 will swing upwardly due to the centrifugal force of the revolving carriers. As the weighted 50 outer end of said lever swings upwardly, the pin 67 will be moved downwardly into the path of the clutch lock 68 and said clutch lock will be released, as will be more fully hereinafter described.

55 If for any reason the tension on the yarn becomes excessive the spring 55 will be pulled inwardly to an abnormal position, thereby rocking the control lever and bringing the arm 52 outwardly against a rigid 60 stop 72 on the inner side of the cover. The continued rotation of the control lever will force its lower end inwardly, the slot 38 permitting this camming action. The movement of the lower end of the control 65 lever will swing the clutch lever lock 70 in-

wardly on its pivot and thereby cause the inner member of the finger 71 to be removed from the stop finger 69. This will release the lever 64 so that the centrifugal action of the rotating carriers will thrust the pin 67 into the path of the clutch lock 68. It is clear, therefore, that the clutch releasing lever 64 will be freed from the clutch lever lock whenever the slack in the yarn becomes too great; whenever the yarn breaks, and whenever there is excessive tension on the yarn. The control lever operates to release the clutch lever lock by rotation in either direction, the excessive yarn tension rotating it in one direction and excessive yarn slack or breakage permitting it to be rotated in the opposite direction by the tension spring.

Whenever the control lever is rotated through excessive tension on the yarn the escapement operating arm 41 will engage the escapement locking lever 60, but this is merely incidental because the yarn is already under an excess tension and it is immaterial whether the spindle is locked. When, however, the clutch lever lock is operated by reason of slack in the yarn or the breakage of the yarn, the escapement locking lever 60 will be released from the arm 41 and will swing into engagement with the escapement locking dog and thereby lock the spindle.

The yarn from the spindle 15 is carried over a rigid bow 73 mounted on the adjacent bar 16. From the bow the yarn is carried upwardly through a guide eye 74 and then over the hook 59 on the end of the tension spring 55. From the hook 59 the yarn passes to the braiding point and is guided over and under the shuttle plates 28 of the inner series of bobbins by means of stationary thread guides 75 and 76 carried by a rigid annular member 77 mounted in the machine frame. The operation of these thread guides and the passage of the yarn from the outer carriers over and under the inner series of carriers are fully described in my hereinbefore mentioned application for patent.

The clutch lock 68 is pivoted on the support 77 and is provided with a locking arm 78 which extends into the path of a pivoted locking dog 79 which is pivoted in the machine frame. The locking dog 79 is pivotally connected to a clutch operating rod 80, said rod being normally forced inwardly by a spring 81. With the locking dog in engagement with the arm 78 as shown in Fig. 1, the clutch members are held locked in engagement. When the clutch lock 68 is swung on its pivot through the operation of one of the pins 67 the dog 79 is released and the spring 81 forces the rod 80 inwardly and disconnects the members of the clutch.

- When the device is in operation spring 55 is subjected to high-frequency oscillations as the yarn alternately passes under and over the oppositely rotating carriers. 5 This oscillating movement is followed by control lever 34, said lever being free and unobstructed during the cycle of movements. As the yarn is drawn through the device the tension on spring 55 is increased, its yarn 10 engaging end is drawn inwardly and its field of spring action is brought nearer to the braiding point, causing control lever 34 to intermittently strike against escapement lock 60 with increasing force until 15 finally the teeth of said escapement lock disengage from those of escapement pawl 50, allowing the latter to move, thereby permitting escapement wheel 43 to turn and thus yield an additional supply of yarn. 20 This additional yarn supply having been obtained, the resulting relaxation in thread tension permits the yarn engaging hook to move outwardly under the influence of the spring 55 and the oscillating field of spring 25 55 to retreat to a point where escapement lock 60 again engages with the escapement pawl, the other end of the pawl engaging with the escapement wheel, thereby preventing further movement of the escapement 30 wheel and stopping the flow of yarn supply. This cycle of movements, with the alternate yielding and stopping of yarn supply, is continuous so long as thread is being drawn through the device. 35 Although control lever 34 moves with the oscillations of spring 55 the work it has to do is much less than that which the spring is called upon to perform. Made from suitable material this control lever should last 40 indefinitely. Escapement lock 60 is made very light in weight, is never subjected to severe strains and has very little inertia to overcome. After the yarn pull has freed the escapement pawl, should the lock fail to 45 promptly and securely reengage with the pawl, the pawl will nevertheless impede the further rotation of the escapement wheel, thus preventing a sudden and excessive flow of yarn such as would cause the machine 50 to stop.
- At all times whether the machine is running or at rest, the yarn is constantly and directly held under tension by spiral spring 55 which is made of flat spring steel and 55 is similar to the usual clock spring. The use of a spring of this kind in a thread tension device has several important advantages. The spring is free from frictional contact with any other part, free from any 60 wear and tear whatever, and functions "in the air". The strongest tensions possible to use in braiding operations and the extent of the oscillating field within which the 65 spring is permitted to move involve strains and movements which are well within the elastic limits of the spring. Such a spring is intensely active yet uniform in action, providing an even tension which reduces the number of accidental yarn breakages and enables the machine to produce a smooth, 70 more even and uniform, and also a stronger article of commerce. Once set and adjusted to any desired tension such a spring is more uniform in action, more constant and dependable than any other kind of device now 75 being used. Also a spring of this kind requires no lubrication.
- This device delivers the yarn both positively and constantly, with an even and gentle flow, under a predetermined tension which is maintained with unequalled uniformity; yet, if for any reason the cycle of operations hereinbefore described is interrupted, or if the tension on a thread becomes much changed, the device will instantly function in such manner as to surely bring the machine to a quick stop. The device constitutes a mechanical unit which is simple in design and easy to assemble; it functions reliably and freely, and the slight 80 wear and strains resulting from its operation are distributed among its coordinated parts in such way that all of the parts will endure for a long period of service. 85
- What I claim is:
1. A tension mechanism for braiding machines comprising a rotatable support, a carrier mounted thereon, a spindle rotatably mounted on the carrier and provided with an escapement wheel, a double escapement pawl mounted on the carrier and adapted to engage the escapement wheel and formed with a locking member, a control lever mounted in the carrier and adapted to rock back and forth in opposite directions, a tension spring mounted on the carrier and connected to the control lever and tending to move said control lever in one direction, a yarn engaging device carried by the said spring the yarn tension tending to move the control lever in opposition to the spring tension, an escapement locking lever mounted in the carrier and yieldingly engaging the locking member of the escapement pawl and adapted to be engaged by the control lever to release the escapement pawl when said control lever is moved by yarn tension, a clutch releasing lever mounted on the carrier, a clutch lever lock mounted on the carrier and adapted to hold the clutch releasing lever in inoperative position, and a clutch operating arm formed on the control lever and adapted to operate the clutch lever lock to release the clutch releasing lever when the control lever is rocked in either direction. 95
  2. A tension mechanism for braiding machines comprising a rotatable support, a carrier mounted thereon, a spindle rotatably mounted on the carrier and provided with 100
  3. A tension mechanism for braiding machines comprising a rotatable support, a carrier mounted thereon, a spindle rotatably mounted on the carrier and provided with 105
  4. A tension mechanism for braiding machines comprising a rotatable support, a carrier mounted thereon, a spindle rotatably mounted on the carrier and provided with 110
  5. A tension mechanism for braiding machines comprising a rotatable support, a carrier mounted thereon, a spindle rotatably mounted on the carrier and provided with 115
  6. A tension mechanism for braiding machines comprising a rotatable support, a carrier mounted thereon, a spindle rotatably mounted on the carrier and provided with 120
  7. A tension mechanism for braiding machines comprising a rotatable support, a carrier mounted thereon, a spindle rotatably mounted on the carrier and provided with 125
  8. A tension mechanism for braiding machines comprising a rotatable support, a carrier mounted thereon, a spindle rotatably mounted on the carrier and provided with 130

nected to the control lever and tending to move said control lever in one direction, a 5 yarn engaging device operatively connected to the control lever whereby the yarn tension tends to move the control lever in opposition to the spring tension, a clutch releasing lever mounted on the carrier, a clutch lever lock mounted on the carrier and adapted to hold the clutch releasing lever in inoperative position, and a clutch operating arm formed 10 on the control lever and adapted to operate the clutch lever lock to release the clutch releasing lever when the control lever is rocked by the tension spring when said 15 spring is relieved of yarn tension

8. A tension mechanism for braiding machines comprising a rotatable support, a carrier mounted thereon, a spindle rotatably mounted on the carrier, a control lever 20 mounted in the carrier and adapted to rock back and forth in opposite directions, a tension spring mounted on the carrier and connected to the control lever and tending to move said control lever in one direction, a 25 yarn engaging device operatively connected to the control lever whereby the yarn tension tends to move the control lever in opposition to the spring tension, a clutch releasing lever pivotally mounted on the carrier 30 on a horizontal pivot and extending outwardly from said pivot, the outer end of said lever being weighted and adapted to be thrown upwardly by the centrifugal force of the rotating carrier support, a clutch 35 lever lock mounted on the carrier and adapted to hold the outer end of the releasing lever in inoperative depressed position, and a clutch operating arm formed on the 40 control lever and adapted to operate the clutch lever lock to release the clutch releasing lever when the control lever is rocked by the tension spring when said 45 spring is relieved of yarn tension.

9. A tension mechanism for braiding machines comprising a rotatable support, a carrier mounted thereon, a spindle rotatably 50 mounted on the carrier, a control lever mounted in the carrier and adapted to rock back and forth in opposite directions, a tension spring mounted on the carrier and connected to the control lever and tending to move said control lever in one direction, a 55 yarn engaging device operatively connected to the control lever whereby the yarn tension tends to move the control lever in opposition to the spring tension, a clutch releasing 60 lever pivotally mounted on the carrier on a horizontal pivot and extending outwardly from said pivot, the outer end of said lever being weighted and adapted to be thrown upwardly by the centrifugal force of the 65 rotating carrier support, a clutch lever lock

mounted on the carrier and adapted to hold the outer end of the releasing lever in inoperative depressed position, and a clutch operating arm formed on the control lever and adapted to operate the clutch lever lock 70 to release the clutch releasing lever when the control lever is rocked by excess yarn tension.

10. A tension mechanism for braiding machines comprising a rotatable support, a 75 carrier mounted thereon, a spindle rotatably mounted on the carrier, a control lever mounted in the carrier and adapted to rock back and forth in opposite directions, a tension spring mounted on the carrier and connected to the control lever and tending to move said control lever in one direction, a 80 yarn engaging device operatively connected to the control lever whereby the yarn tension tends to move the control lever in opposition to the spring tension, a clutch releasing lever pivotally mounted on the carrier on a horizontal pivot and extending outwardly from said pivot, the outer end of 85 said lever being weighted and adapted to be thrown upwardly by the centrifugal force of the rotating carrier support, a clutch lever lock mounted on the carrier and adapted to hold the outer end of the releasing lever in inoperative depressed position, and a clutch operating arm formed 90 on the control lever and adapted to operate the clutch lever lock to release the clutch releasing lever when the control lever is rocked by the tension spring when said 95 spring is relieved of yarn tension.

11. A tension mechanism for braiding machines comprising a rotatable support, a carrier mounted thereon, a spindle rotatably mounted on the carrier and provided with 100 an escapement wheel, an escapement pawl mounted on the carrier and adapted to engage the escapement wheel, a control lever mounted on the carrier and adapted to move back and forth in opposite directions from 105 its normal position, a tension spring mounted on the carrier and connected to the control lever and tending to move said lever in one direction, a yarn engaging device operatively connected to the control lever 110 whereby the yarn tension tends to move the control lever in opposition to the tension spring, and an escapement locking lever mounted in the carrier and normally yieldingly engaging the said pawl and adapted 115 to be engaged by the control lever to release said pawl when the control lever is moved by yarn tension.

12. A tension mechanism for braiding machines comprising a rotatable support, a 120 yarn spindle rotatably mounted and carried by said support, a control lever, a tension spring connected to said lever, a yarn engaging device operatively connected to the 125 control lever whereby the yarn tension tends 130

to move the control lever in opposition to the spring tension, clutch releasing mechanism, and means whereby the control lever will operate said clutch releasing mechanism 5 when the control lever is rocked in one direction by excess yarn tension and in the other direction by the tension spring when said spring is relieved of yarn tension.

13. A tension mechanism for braiding machines comprising a rotatable support, a 10 yarn spindle rotatably mounted and carried by said support, a control lever, a tension spring arranged in a spiral coil and having its inner end rigidly secured, its 15 outer end extending freely outwardly and carrying a yarn engaging device near its outer end, said outer end being connected to the control lever whereby the yarn tension will tend to move the control lever in 20 opposition to the spring tension, and spindle locking means adapted to be operated by the control lever to release the spindle when said lever is moved by yarn tension, said spindle locking means operating to lock the 25 spindle when the control lever is moved by the tension spring.

14. A tension mechanism for braiding machines comprising a rotatable support, a 30 yarn spindle rotatably mounted and carried by said support, a control lever, a tension spring arranged in a spiral coil and having its inner end rigidly secured, its outer end extending freely outwardly and carrying a yarn engaging device near its outer end, 35 said outer end being connected to the control lever whereby the yarn tension will tend to move the control lever in opposition to the spring tension, clutch releasing mechanism, and means whereby the control lever 40 will operate said clutch releasing mechanism when the control lever is rocked in one direction by excess yarn tension and in the other direction by the tension spring when said spring is relieved of yarn tension.

45 15. A tension mechanism for braiding machines comprising a rotatable support, a carrier mounted thereon, a spindle rotatably mounted on the carrier, a control lever mounted in the carrier and adapted to rock 50 back and forth in opposite directions, a tension spring mounted on the carrier and connected to the control lever and tending to move said control lever in one direction, a yarn engaging device operatively connected 55 to the control lever whereby the yarn tension tends to move the control lever in opposition to the spring tension, a clutch releasing mechanism mounted on the carrier and adapted to be moved into operative position by the centrifugal force of the rotating carrier support, a movable lock mounted on the carrier and adapted to hold the clutch 60 releasing mechanism in inoperative position, and means whereby the control lever will operate the lock to free the clutch releasing mechanism when the control lever is rocked by the tension spring when said spring is relieved of yarn tension.

mechanism when the control lever is rocked by excess yarn tension.

16. A tension mechanism for braiding machines comprising a rotatable support, a 70 carrier mounted thereon, a spindle rotatably mounted on the carrier, a control lever mounted in the carrier and adapted to rock back and forth in opposite directions, a tension spring mounted on the carrier and connected to the control lever and tending 75 to move said control lever in one direction, a yarn engaging device operatively connected to the control lever whereby the yarn tension tends to move the control lever in opposition to the spring tension, a clutch releasing mechanism mounted on the carrier and adapted to be moved into operative 80 position by the centrifugal force of the rotating carrier support, a movable lock mounted on the carrier and adapted to hold the clutch releasing mechanism in inoperative position, and means whereby the control lever will operate the lock to free the clutch 85 releasing mechanism when the control lever is rocked by the tension spring when said 90 spring is relieved of yarn tension.

17. A tension mechanism for braiding machines comprising a rotatable support, a 95 yarn spindle rotatably mounted and carried by said support, a control lever, a tension 100 spring connected to said lever, a yarn engaging device operatively connected to the control lever whereby the yarn tension tends to move the control lever in opposition to the spring tension, a clutch releasing mechanism carried by and rotating with the said support and adapted to be moved into operative position by the centrifugal force of the rotating support, a movable lock adapted to hold the clutch releasing mechanism in inoperative 105 position, and means whereby the control lever will operate the lock to free the clutch releasing mechanism when the control lever is rocked by recess yarn tension.

18. A tension mechanism for braiding machines comprising a rotatable support, a 110 yarn spindle rotatably mounted and carried by said support, a control lever, a tension spring connected to said lever, a yarn engaging device operatively connected to the control lever whereby the yarn tension tends to move the control lever in opposition to the spring tension, a clutch releasing mechanism carried by and rotating with the said support and adapted to be moved into operative 115 position by the centrifugal force of the rotating support, a movable lock adapted to hold the clutch releasing mechanism in inoperative position, and means whereby the control lever will operate the lock to free the clutch 120 releasing mechanism when the control lever is rocked by the tension spring when said spring is relieved of yarn tension.

19. A tension mechanism for braiding machines comprising a rotatable support, a car- 125

- rier mounted thereon, a spindle rotatably mounted on the carrier, a control lever mounted in the carrier and adapted to rock back and forth in opposite directions, a tension spring mounted on the carrier and connected to the control lever and tending to move said control lever in one direction, a yarn engaging device carried by said spring, the yarn tension tending to move the control lever in opposition to the spring tension, a clutch releasing lever pivotally mounted on the carrier on a horizontal pivot and extending outwardly from said pivot, the outer end of said lever being weighted and adapted to be thrown upwardly by the centrifugal force of the rotating carrier support, a pin carried by the inner end of said clutch releasing lever, means adapted to be operated by said pin to stop the rotatable support, a clutch lever lock mounted on the carrier and adapted to hold the outer end of the releasing lever in inoperative depressed position, and a clutch operating arm formed on the control lever and adapted to operate the clutch lever lock to release the clutch releasing lever when the control lever is rocked by excess yarn tension.
20. A tension mechanism for braiding machines comprising a rotatable support, a carrier mounted thereon, a spindle rotatably mounted on the carrier, a control lever mounted in the carrier and adapted to be rocked back and forth in opposite directions, said control lever being formed with an escapement operating arm a clutch operating arm and a tension arm, a tension spring mounted on the carrier and loosely engaging the tension arm of the control lever and tending to move said control lever in one direction, a yarn engaging device carried by said spring, the yarn tension tending to move the control lever in opposition to the spring tension, an escapement locking lever mounted in the carrier and normally locking the spindle and adapted to be engaged by the escapement operating arm of the control lever to release the spindle when said control lever is moved by yarn tension, a clutch releasing lever mounted in the carrier, and a clutch lever lock mounted in the carrier and normally holding the clutch releasing lever in inoperative position and adapted to be engaged by the clutch operating arm of the control lever to release the clutch releasing lever when the control lever is rocked in either direction.
21. A tension mechanism for braiding machines comprising a rotatable support, a spindle carried by said support, a control lever rockably supported adjacent the spindle, a tension spring connected to said control lever and tending to move it in one direction, a yarn engaging device operatively connected to the control lever whereby the yarn tension will tend to move the control lever in opposition to the tension spring, a spindle escapement mechanism adapted to be released by the movement of the control lever in one direction, and a clutch mechanism adapted to be operated by the control lever when said lever is rocked in either direction.
22. A tension mechanism for braiding machines comprising a rotatable power driven support, a spindle carried by said support, a control lever rockably supported adjacent the spindle, a tension spring connected to said control lever and tending to move it in one direction, a yarn engaging device operatively connected to the control lever whereby the yarn tension will tend to move the control lever in opposition to the tension spring, a spindle escapement mechanism adapted to be released by the movement of the control lever in one direction, and a mechanism to cause the driving power to be cut off from the rotatable support when the said control lever is rocked in either direction.
23. A tension mechanism for braiding machines comprising a rotatable power driven support, means carried by the rotatable support adapted to be operated by centrifugal force to cut off the driving power from the rotatable support, and means controlled by the yarn tension to hold the said power cut-off means inoperative during normal yarn tension and to render it operative upon a predetermined variation in yarn tension.
24. A tension mechanism for braiding machines comprising a power driven rotatable support, a yarn spindle carried by said support, means carried by the rotatable support adapted to be operated by centrifugal force to cut off the driving power from the rotatable support, and means controlled by the yarn tension to hold the said power cut-off means inoperative during normal yarn tension and to render it operative upon a predetermined increase or decrease in yarn tension.
25. A tension mechanism for braiding machines comprising a rotatable power driven support, a yarn spindle, a yarn tension controlled spindle escapement, means carried by the rotatable support adapted to be operated by centrifugal force to cut off the driving power from the rotatable support, and means controlled by the yarn tension to hold the said power cut-off means inoperative during normal yarn tension and to render it operative upon a predetermined increase or decrease in yarn tension.
26. A tension mechanism for braiding machines comprising a rotatable support, a carrier mounted thereon, a spindle rotatable mounted on the carrier, a clutch releasing lever pivotally mounted on the carrier on a horizontal pivot and extending outwardly from said pivot, the outer end of said lever being weighted and adapted to be thrown

upwardly by the centrifugal force of the rotating carrier support, a clutch lever lock mounted on the carrier and adapted to hold the outer end of the releasing lever in inoperative depressed position during normal yarn tension, and means controlled by yarn tension to operate the clutch lever lock to release the clutch releasing lever upon a predetermined variation in yarn tension, whereby the outer end of the clutch releasing lever will be thrown upwardly to operative position by the centrifugal force due to the speed of the rotating carrier support.

27. A tension mechanism for braiding machines comprising a rotatable support, a carrier mounted thereon, a spindle rotatably mounted on the carrier, a control device movably mounted on the carrier, a tension spring mounted on the carrier and connected

to the control device and tending to move said control device in one direction, a yarn engaging device operatively connected to the control device whereby the yarn tension will tend to move the control device in opposition to the tension spring, a clutch releasing lever mounted on the carrier, and a clutch lever lock mounted on the carrier and adapted to hold the clutch releasing lever in inoperative position, the said control device being adapted to move said clutch lever lock to release the clutch releasing lever upon an increase in yarn tension above a predetermined maximum degree or a decrease in yarn tension below a predetermined minimum degree.

In testimony whereof I hereunto affix my signature.

FREDERICK KLEIN.
